[57] CLAIM

The ornamental design for an airway airflow indicator for facilitating blind nasal or blind oral intubation of the trachea and the like, substantially as shown and described.

DESCRIPTION

FIG. 1 is a front perspective view of an airway airflow indicator for facilitating blind nasal or blind oral intubation of the trachea and the like, showing my new design;

FIG. 2 is a top plan view thereof;

FIG. 3 is a bottom view thereof;

FIG. 4 is a vertical sectional view thereof, taken along line 4—4 of FIG. 2; and

FIG. 5 is a perspective view of one of the interfitting halves of the claimed device.
